UNITED STATES PATENT OFFICE

158,976

TEXTILE FABRIC OR SIMILAR ARTICLE

Rose Lacher, New York, N. Y.

Application December 31, 1949, Serial No. 6,950

Term of patent 3½ years

(Cl. D92—1)

To all whom it may concern:

Be it known that I, Rose Lacher, a citizen of the United States of America, residing in New York city, county of New York, and State of New York, have invented a new, original, and ornamental Design for a Textile Fabric or Similar Article, of which the following is a specification, reference being had to the accompanying drawing, forming part thereof, wherein:

The figure on the drawing is a plan view of a textile fabric showing my new design. The dot and dash lines on the drawing outline a design unit, which unit is repeated in regular succession as indicated by the extensions beyond the unit boundaries.

I claim:

The ornamental design for a textile fabric or similar article, substantially as shown and described.

ROSE LACHER.
